UNITED STATES PATENT OFFICE.

HENRY W. STONE, OF SAN DIEGO, CALIFORNIA.

PUNCTURING, DISPENSING, AND SEALING DEVICE.

1,048,226.

Specification of Letters Patent. Patented Dec. 24, 1912.

Application filed September 5, 1911. Serial No. 647,527.

To all whom it may concern:

Be it known that I, HENRY W. STONE, a citizen of the United States of America, residing at San Diego, in the county of San Diego and State of California, have invented certain new and useful Improvements in Puncturing, Dispensing, and Sealing Devices, of which the following is a specification.

10 This invention relates to a puncturing, dispensing, and sealing device, particularly adapted for use in dispensing condensed or evaporated milk or cream, though it is of course capable of use in dispensing any liquid from a can.

15 The object of the invention is to provide a structure adapted to be forced through the top of the can and to have an air-tight engagement therewith, together with a valve 20 which permits the passage of liquid from the can when the can is inverted, but serves to seal the discharge passage when the can is returned to an upright position.

25 Further objects and advantages of the invention will be set forth in the detailed description which now follows.

30 In the accompanying drawing, Figure 1 is a sectional view of the device constructed in accordance with the invention, and Fig. 30 2 is a side elevation at right angles to Fig. 1.

Like numerals designate corresponding parts in both of the figures of the drawing.

Referring to the drawing, the numeral 5 designates a can such as is ordinarily employed for containing condensed or evaporated milk.

40 The puncturing and dispensing device comprises a head 6, a threaded shoulder 7, and a quill-like shank 8, the lower end of the shank 8 being beveled at 9 to form a puncturing point 10 at the lower end of said shank. The shank has a discharge passage 11 formed therethrough and is slotted along one side at 12 for a purpose hereinafter described. The upper end of the passage 11 terminates in a flaring valve seat 13 upon which a ball valve 14 is adapted to have a seating. A cage 15 is soldered or otherwise secured to the head 6 and provides means 45 for retaining the ball valve 14 in operative position. A rubber or other flexible washer 16 is disposed between the under side of the head 6 and the top of the can 5.

50 It will be seen that the members of the cage 15 are formed of stout material, and that the upper portion of the cage lies above

the ball valve. The side members of the cage are disposed vertically, and this cage provides a portion for the user to strike against with a hammer or other tool in 60 forcing the shank through the material of the can, and without striking the check valve.

65 The operation of the device is as follows: When it is desired to dispense milk from the can 5, the structure shown in Fig. 2 is forced through the top of the can, the point 10 making the necessary cut for this purpose. After the shank 8 has been forced downwardly far enough for the screw 70 threads 7 to take a hold in the top of the can, the device is rotated to screw it into the top of the can and thereby press the washer 16 between the head 6 and the can. This forms an air-tight joint at 75 this point. If the can be turned upon its side or inverted, the contents will flow through the passage 11, it being understood that inversion of the can causes the ball valve 14 to move away from the seat 13. 80 This ball valve, however, returns to its seat when the can is again turned to its upright position and serves to seal the can. The slot 12 is provided to permit all of the contents of the can to pass therefrom. In other 85 words, after the contents of the can get low, the slot 12 still provides an entrance to the passage 11.

90 It is a well known fact that evaporated or condensed milk rapidly deteriorates if left exposed to the air. The structure herein shown and described not only provides a highly efficient means for puncturing the can, but serves to seal the can except when the contents thereof are being discharged. 95

95 From the foregoing description, it will be seen that simple and efficient means are herein provided for accomplishing the objects of the invention, but while the elements shown and described are well adapted to 100 serve the purposes for which they are intended it is to be understood that the invention is not limited to the precise construction set forth, but includes within its purview such changes as may be made within the 105 scope of the appended claims.

Having described my invention, what I claim is:

110 1. In a device of the character described, the combination with a tubular member, comprising a shank having a piercing point in its lower end, a head having a valve seat

formed therein at its upper end and a threaded shoulder between the shank and the head, of a compressible washer located beneath said head, there being a slot formed 5 through one side of said tubular member throughout the shank and the threaded shoulder, a ball valve coacting with said valve seat, and a cage carried by the head for retaining said ball valve in position.

10 2. In a device of the character described, the combination with a tubular member comprising a head portion, an elongated shank portion and a threaded shoulder portion, disposed between the head portion 15 and the shank portion, the lower extremity of the shank portion being sharply beveled to form a piercing point, and the shoulder portion and the shank portion having a con-

tinuous vertical slot formed through their 20 wall, the upper end of the head portion being provided with a concave valve seat, a ball valve seated upon said valve seat, a cage 25 comprising arched members which overlie the ball, and which are rigidly secured at their lower portions to said head, said cage serving the double purpose of preventing accidental displacement of the ball, and providing a driving element upon which to drive in forcing the piercing point of the shank into a can.

In testimony whereof I affix my signature in presence of two witnesses.

HENRY W. STONE.
